CLAIM

The ornamental design for a skewer, as shown and described.

DESCRIPTION

FIG. 1 is a perspective view of a skewer in an open configuration in accordance with the present design; FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof;

FIG. 7 is a right side elevation view thereof;

FIG. 8 is a perspective view of a skewer in a closed configuration in accordance with the present design;

FIG. 9 is a top plan view thereof;

FIG. 10 is a bottom plan view thereof;

FIG. 11 is a rear elevation view thereof;

FIG. 12 is a front elevation view thereof;

FIG. 13 is a left side elevation view thereof; and,

FIG. 14 is a right side elevation view thereof.

The broken lines shown are included for the purpose of illustrating portions of the skewer that forms no part of the claimed design.

1 Claim, 6 Drawing Sheets
